(57) **CLAIM**

The ornamental design for a portable earphone holder.

DESCRIPTION

FIG. 1 is a front perspective view of a portable earphone holder shown attached to a rigid storage case and stand shown in an unfolded position.

FIG. 2 is a front perspective view of the portable earphone holder.

FIG. 3 is a top plan view of the invention.

FIG. 4 is a left side elevation view of the invention;

FIG. 5 is a bottom plan view of the invention.

FIG. 6 is front elevational view of the invention.

FIG. 7 is a rear elevational view of the invention; and,

FIG. 8 is a right side elevational view of the invention.

The broken lines showing a storage case and a pair of ear buds are for the purposes of illustrating environment and form no part of the claimed design.
